UNITED STATES PATENT OFFICE.

BENJAMIN FISCHMAN, OF NEW YORK, N. Y.

DESIGN FOR A SLIDE-BUCKLE.

SPECIFICATION forming part of Design No. 34,610, dated June 4, 1901.

Application filed April 30, 1901. Serial No. 58,221. Term of patent 3½ years.

To all whom it may concern:

Be it known that I, BENJAMIN FISCHMAN, a citizen of the United States, and a resident of New York city, county and State of New York, have invented a new and original Design for Slide-Buckles, of which the following is a specification, reference being had to the accompanying drawings, in which—

Figure 1 is a perspective view of my newly-designed slide-buckle; and Fig. 2 is a longitudinal section on line 2 2, Fig. 1.

As represented in the drawings, the leading feature of the design consists of an oval frame *a*, having a flat inner face and a rounded outer face. A bar *b*, flat in cross-section and having curved ends *b'*, extends longitudinally

over the frame and projects in front thereof. From the bar *b* projects a hook *c*, the beak of which extends over portion of bar *b* and parallel thereto. This beak has a flat inner face, 20 a rounded outer face, and it tapers from end to end.

What I claim is—

The design for a slide-buckle, substantially as herein shown and described. 25

Signed by me at New York city, county and State of New York, this 29th day of April, 1901.

B. FISCHMAN.
